Jacques L. Lemerle, Attorney

UNITED STATES PATENT OFFICE.

JACQUES LOUIS LEMERLE, OF VINCENNES, FRANCE.

BELLows.

Application filed May 15, 1922. Serial No. 561,006.

To all whom it may concern:

Be it known that I, JACQUES LOUIS LEMERLE, citizen of the French Republic, residing at Vincennes, Department of Seine, France, have invented certain new and useful Improvements in Bellows, of which the following is a specification.

This invention relates to bellows and it has to do more particularly, though not exclusively, with bellows intended for use in connection with railway-cars, known as car diaphragms in order to form a tight joint between the vestibules of cars coupled together.

An object of the invention is to simplify, and, therefore, reduce the cost of manufacture of, such devices.

The invention consists chiefly: in riveting, or otherwise suitably fastening into the folds 20 of the bellows above referred to, the usual strengthening bands in such a manner that the rivets will be distributed along the folding lines of the bellows and will not interfere with the folding of the folds of the 25 bellows throughout the entire depth, but will prevent a sharp bend in the material of the bellows.

The invention comprises other secondary 30 novel features, which will be more fully set forth in the course of this specification and pointed out in the appended claims.

The invention has more particularly in view the production, as new articles of manufacture, of bellows embodying such new arrangement and features, as well as of the specific elements making up the construction 35 of such bellows.

The invention will be readily understood by means of the following description and 40 by reference to the accompanying drawings, said description and drawings being, of course, given merely by way of example.

In said drawings:

Figure 1 shows, in partial section, the 45 usual bellows made of folded or chased leather.

Figure 2 is a similar view of a bellows made in accordance with the invention.

In constructing, for example, intercommunication-bellows for railway-cars, as 50 shown in Fig. 2 which illustrates the preferred embodiment of the invention, I manufacture, in the usual manner, the bellows-head *a* of leather, canvas, or other suitable material. I also produce from flat iron or

steel approximately U-shaped strengthening bands *b* to be placed in each fold of the bellows.

Instead of riveting these bands to the bellows-leather in the usual manner, that is 60 to say, as shown in Figure 1, upon the leather-portion situated between two bends (outer and inner), I arrange rivets along the outer bend itself, as shown in Fig. 2.

For this purpose, I provide the shanks of 65 the rivets *c* with means for fastening them to the strengthening band *b*, and, in order to obtain this result I either provide the shank of the rivet with a fork embracing 70 the strengthening band and secured thereto by any suitable means; or fasten the rivet directly on the band by soldering or other suitable means; or form the rivet with a stirrup-shaped part adapted to embrace the band, the free ends of said rivet being adapted 75 to be bent down, so as to form the head of the rivet. The bodies of these rivets thus fastened onto the band *b* extend through holes punched in the leather along its outer bend, and the riveting is effected in the 80 usual way, preferably after having placed upon the leather a corresponding number of washers, or, a continuous metallic band *e* provided with holes for the passage of the rivet-bodies, in such a manner that said 85 washers or band, when the rivet-heads have been formed, will be interposed between the latter and the leather.

The bellows is afterwards completed, in 90 the ordinary way, by uniting together the upper and lower heads by means of lateral elements made of leather or canvas, which elements may be strengthened in the manner above explained with reference to the heads.

By the construction just described an intercommunication-bellows is obtained, the 95 expansion of which takes place under better conditions than heretofore and without any risk that the leather or canvas will become torn out by the rivet-heads, as frequently happens at the point *d* (Figure 1) in the usual forms. Moreover the rivet-heads protect said leather or canvas from any friction against the sheath of the bellows.

Obviously the invention is not restricted to the modes of application and realization herein described and shown, but may take other forms coming within the scope of the 100 appended claims.

Claims:

1. An accordion-shaped bellows provided between its folds with flat strengthening bands lying in the planes of the outer folding lines of the bellows, and rivets distributed along said outer folding lines for securing said bands to said bellows.
2. An accordion-shaped bellows provided between its folds with strengthening bands, and rivets for securing said bands to said bellows, said rivets being distributed along the folding lines of the bellows and each being provided at its inner end with a fork or

stirrup-shaped part embracing one of the strengthening bands and fastened thereto.

15

3. In a device of the character described, a collapsible accordion-shaped member, provided with strengthening bands, and rivets arranged along the outer bend between adjacent folds and each having on its inner end means embracing one of said bands and forming a rounded shoulder thereon.

In testimony whereof I have hereunto set my hand.

JACQUES LOUIS LEMERLE.
